HUMIDIFIER

Gerald W. Skilbeck, Kenosha, Wis.

Application July 1, 1944, Serial No. 543,137

13 Claims. (Cl. 237—78)

1

This invention relates to humidifiers and refers particularly to humidifiers designed to correct overly dry atmospheric conditions in homes, shops, offices and the like.

Humidifiers for this purpose have been available in the past as evidenced by Patent No. 2,111,437, issued to Gerald W. Skilbeck March 15, 1938, but heretofore there has been no practical humidifier suitable for use on hot water heating systems.

It is therefore the chief purpose of this invention to provide a humidifier which, although not limited thereto, is especially adaptable for use with hot water heating systems.

More specifically, it is an object of this invention to provide a humidifier which is a self contained unit adapted to be attached to a radiator or other element of a hot water heating system and which incorporates a valved port for emitting hot water from the interior of the main chamber of the humidified and derived from the heating source, the valve being controlled by the weight of a collecting cup in which excess water accumulates.

Another object of this invention is to provide a humidifier of the character described having a large heated surface area covered by a bibulous wrap so that water caused to flow over the exterior thereof will be evaporated in large volume.

Still another object of this invention is to provide a humidifier which is simple and wherein the valve controlling mechanism is rugged and not easily injured.

A further object of this invention is to provide a humidifier of the character described which, by virtue of its simplicity in design and construction, may be manufactured at a nominal cost.

With the above and other objects in view, which will appear as the description proceeds, the invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawing illustrates one complete example of the physical embodiment of the invention constructed according to the best mode so far devised for the practical application of the principles thereof, and in which:

Figure 1 is a view illustrating a section of an ordinary hot water radiator and illustrating the application of this invention thereto;

2

Figure 2 is an enlarged view, partially in longitudinal section, of the humidifier, per se; and

Figure 3 is a cross-sectional view taken through Figure 2 on the plane of the line 3—3.

Referring now more particularly to the accompanying drawing in which like numerals indicate like parts, the numeral 5 designates generally the humidifier unit, which is adapted to be mounted on and supported from a radiator 6 or any other element of a hot water heating system in such a manner that the hot water or other heating medium circulates through the humidifier.

The humidifier comprises a cylindrical tube 7 closed at both ends and provided with an open ended hollow core 8 extending entirely therethrough. Near its opposite ends the tube 7 has pipe nipples 9 and 10 projecting laterally by which the structure is mounted on the radiator or other element of the heating system and through which hot water from the heating system is permitted to circulate through the tube 7. The tube 7 preferably has a thin wall so as to take full advantage of the heat of the water or other heating medium circulating therethrough.

At its upper portion the tube has an outlet 11 to which a duct 12 is secured. This duct has a reverse bend or gooseneck portion providing a water trap, and its free end is secured as at 13 to a nozzle 14. The nozzle 14 is supported by a bracket 15 on the upper end of the humidifier unit and projects through this bracket and the bottom wall of a troughlike unit 16 seated on top of the bracket. The outer end of this troughlike unit is closed, but its inner end, which terminates adjacent to the axis of the tube 7, is open so that water discharged by the nozzle 14 may flow onto the tube 7 and then down over its side wall.

A lever 17 is pivotally mounted as at 18 within the troughlike unit 16 to swing toward and from the top of the nozzle so that a valve disc 19 carried on the underside of the lever may be moved into and out of sealing engagement with the nozzle. A spring 20 confined between the top of the troughlike unit and a washer 21 yieldingly urges the lever and consequently the valve disc to its raised "valve open" position. The washer 21 bears against the head of an adjusting screw 22 threaded into the lever so that by means of the screw the spring tension with which the valve is held open may be adjusted.

The entire tube or at least its entire cylindrical side wall has a suitable absorbent or bibulous ma-

terial 23 applied thereto to become saturated by the water flowing down over the tube and thus provide a large surface area from which the water is constantly evaporated by the heat of the unit. The bibulous wrapping 23 may be of any suitable material as, for instance, cloth strips wound spirally around the tube. Any excess water not evaporated is accumulated in a cup 24 loosely telescoped over the bottom end of the tube and supported by a rod or link 25 which extends up through the hollow core 8 to be connected to the free end of the lever 17 as at 26. Thus the weight of the cup and its contents reacts against the tension of the spring 20 to close the valve and shut off the supply of water whenever the water in the cup 24 reaches a predetermined level. The rate of water flow over the unit is, therefore, coordinated with the rate of evaporation. The faster the water is evaporated the more is permitted to flow over the unit, and vice versa.

After the valve has been closed in the manner defined, it is reopened as soon as enough of the water contained in the cup 24 has been evaporated to allow the spring 20 to overbalance the weight of the cup and its contents. The evaporation of the water in the cup is brought about jointly by the direct application of heat to the lower end of the tube 7 which extends into the water, and by capillary attraction carrying the water up the bibulous wrap of the tube as it begins to dry.

It is to be observed that as the bibulous wrap dries out the rate of evaporation therefrom decreases and, consequently, the water in the tube 7 is not cooled as rapidly and does not circulate as fast as when the cooling effect of evaporation is present to its fullest extent. Hence, the lower end of the tube 7 becomes hotter and accelerates evaporation from the cup during this period.

A guard 27 is preferably provided for the unit being held in place by screws 28 threaded into studs 29 secured to the lower portion of the tube 7 and by a screw 30 threaded into a lug 31 extended from the end wall of the troughlike unit 16.

From the foregoing description, taken in connection with the accompanying drawing, it will be readily apparent to those skilled in the art, that this invention provides a humidifier especially well adapted for use with hot water heating systems. However, it will also be clear that the invention is not limited to use with hot water heating systems. For instance, the water supplied to the nozzle 14 may be conducted thereto from any suitable source not necessarily the interior of the tube 7, and the tube 7 need not be heated by circulating hot water therethrough, but might well be heated by means of combustion gases circulated through the interior thereof.

What I claim as my invention is:

1. A humidifier comprising: an upright hollow chamber adapted to contain hot water; means for connecting the chamber with a source of hot water so that the chamber is kept full of hot water at all times; an outlet leading from the upper portion of the chamber; means for conducting water issuing from the outlet on top of the chamber to flow down over the walls thereof and be evaporated by the heat of the chamber; a valve for closing the outlet; means biasing the valve to open position; a cup at the bottom of the chamber in which excess water flowing down over the chamber accumulates; and a connection be-

tween the cup and the valve so that the weight of the cup and water contained therein opposes the biasing means to close the valve when a predetermined amount of water accumulates in the cup.

2. A humidifier comprising: an upright tubular heat exchanger; means for circulating a heating medium through said heat exchanger so that the surface thereof is kept heated; a bibulous sheath around the heat exchanger; means for supplying water to the top of the heat exchanger to flow down over its bibulous sheath and be evaporated; a valve for controlling the supply of water to the top of the heat exchanger; means mounting the valve in fixed relationship to the heat exchanger; means biasing the valve to open position; a cup in position to catch water which drips from the heat exchanger and movable relative to the heat exchanger; and a connection between the cup and the valve so that the weight of the cup and its contents oppose the biasing means and thus regulate the position of the valve to control the flow of water to the heat exchanger.

3. A humidifier comprising: an upright tubular heat exchanger having a hollow core opening to both its ends; means for circulating a heating medium through the heat exchanger; means for supplying water to the top of the heat exchanger to flow down over the sides thereof and be evaporated; a valve biased to open position for controlling the flow of water to the top of the heat exchanger; a cup in position to catch excess water flowing down over the heat exchanger; and a link extending through the tubular core of the heat exchanger and connecting the cup with the valve so that the weight of the cup and its contents oppose the bias of the valve and thereby regulate the position of the valve in accordance with the volume of water flowing over the heat exchanger.

4. A humidifier comprising: a hollow tube closed except for inlet and outlet parts adjacent to its opposite ends; means communicating with said parts for mounting the tube in an upright position and for circulating a heating medium through the interior thereof; a bibulous wrap covering the upright exterior surfaces of the tube; a water supply duct terminating above the tube so that water issuing therefrom flows down over the sides of the tube to saturate its bibulous wrap; a cup in position to catch excess water dripping from the wrapped tube; and means responsive solely to the volume of water in said cup for regulating the supply of water to said duct.

5. A humidifier comprising: a hollow upright tube closed at both ends; means for circulating a heating medium through the hollow tube; a bibulous wrap covering the side walls of the tube; a trough with its mouth in position to discharge on top of the tube; a water supply nozzle opening through the bottom of the trough for supplying water to the trough so that water so supplied flows down over the bibulous wrap to be evaporated; a pivoted lever mounted in the trough above the nozzle; a valve on said pivoted lever in position to close the nozzle when the lever is in a predetermined lowered position; a spring acting on the lever to hold the same raised and the valve off the nozzle; a water accumulation cup separate from the tube but in position to catch excess water which drips from the tube; and a connection between the cup and said lever so that the weight of the cup and its contents opposes the spring and thus regulates the position

of the valve in accordance with the volume of water contained in the cup.

6. A humidifier for hot water heating systems comprising: a tubular upright heat exchanger; common means for connecting the heat exchanger to an element of a hot water heating system and for enabling the circulation of hot water from the heating system through said heat exchanger; an outlet in the upper portion of the heat exchanger; a duct leading from said outlet and adapted to discharge water from the interior of the heat exchanger on top of the heat exchanger to flow down over the sides of the heat exchanger and be evaporated; a valve biased to open position for controlling the flow of water through said duct; an excess water accumulation cup in position to catch water which drips from the bottom of the heat exchanger; and a connection between the cup and said valve so that the weight of the cup and its contents oppose the biasing force of the valve and thereby regulate the position of the valve in accordance with the volume of water contained in the cup.

7. A humidifier for hot water heating systems comprising: a hollow tube closed at its ends and having a hollow core extending therethrough from end to end; tubular means opening to the interior of the tube for connecting the tube to an element of a hot water heating system and for circulating hot water from the system through the tube; an outlet at the upper portion of the tube; a duct connected to the outlet and having a gooseneck portion forming a water trap; a valve nozzle at the outer end of the duct at an elevation above that of the tube; means for conducting water issuing from the nozzle onto the top of the tube to flow down over the sides thereof; a valve for closing the nozzle; a spring biasing the valve to open position; a cup in position to catch excess water dripping from the bottom of the tube; and a link within the hollow core of the tube connecting the cup with the valve so that the weight of the cup and its contents opposes the spring and regulates the position of the valve in accordance with the volume of water contained in the cup.

8. A humidifier for hot water heating systems comprising: a hollow tube closed at its ends and having a hollow core extending therethrough from end to end; tubular means opening to the interior of the tube for connecting the tube to an element of a hot water heating system and for circulating hot water from the system through the tube; an outlet at the upper portion of the tube; a duct connected to the outlet and having a gooseneck portion forming a water trap; a valve nozzle at the outer end of the duct at an elevation above that of the tube; means for conducting water issuing from the nozzle onto the top of the tube to flow down over the sides thereof; a valve for closing the nozzle; a spring biasing the valve to open position; a cup in position to catch excess water dripping from the bottom of the tube; a link within the hollow core of the tube connecting the cup with the valve so that the weight of the cup and its contents opposes the spring and regulates the position of the valve in accordance with the volume of water contained in the cup; and a bibulous wrap covering the exterior walls of the tube to become saturated by the water flowing over the tube.

9. A humidifier comprising: a heating element; a bibulous wrap providing the external surface for the heating element; means for supplying water to the upper portion of the heat-

ing element to flow down over the bibulous wrap on its exterior for evaporation by the heat of the heating element so that the heating element and its wrap act as a humidifier unit; a valve supported in fixed relationship to the humidifier unit for controlling the supply of water flowing to the upper portion of the heating element; a cup adjacent to the bottom of the humidifier unit in position to receive excess water flowing down over the unit and to accumulate such water therein, said cup being movable relative to the humidifier unit; and a connection between said cup and the valve by which the cup is movably supported adjacent to the bottom of the humidifier unit and by which downward motion of the cup with respect to the unit in response to the accumulation of water in the cup is translated into closing motion of the valve, and whereby the valve is closed upon accumulation of a predetermined amount of water in the cup.

10. A humidifier comprising: an upright tubular heat exchanger; means providing for circulation of a heating medium through said heat exchanger so that the surface thereof may be heated; a bibulous sheath around the heat exchanger; means for supplying water to the top of the heat exchanger to flow down over its bibulous sheath and be evaporated so that the heating element and its sheath act as a humidifying unit; a valve for controlling the supply of water to the top of the heat exchanger, said valve having a movable actuator by which the valve is controlled; and means supported from the valve actuator for movement relative to the humidifying unit for controlling said valve in accordance with the excess of water supplied to the bibulous sheath.

11. A device of the character described, comprising: a humidifying element having substantially upright exterior walls adapted to be subjected to heat with the surface of said walls formed to retard the flow of water supplied to the element; a water supply duct terminating adjacent to the upper end portion of the humidifying element so that water issuing from the duct flows down over the surface of the element; a valve fixed with respect to the humidifying element for controlling the supply of water to said duct; means biasing the valve to open position; an excess water accumulation receptacle in position to catch and accumulate excess water flowing down over the exterior surfaces of the humidifying element, said receptacle being movable with respect to the humidifying element; and a connection between the receptacle and the valve by which the receptacle is supported independently of the humidifying element and by which motion of the receptacle relative to the element in response to accumulation of water in the receptacle actuates the valve toward closed position, whereby the weight of the receptacle and its contents opposes the biasing means to coordinate the position of the valve with the volume of the water flowing over the surface of the humidifying element.

12. A device of the character described comprising: a hollow humidifying element having a moisture retaining surface and adapted to be internally heated so as to diffuse water on the exterior of the element into the atmosphere; water supply means fixed with respect to the humidifying element for delivering water to the upper portion thereof to flow down said surface thereof for evaporation from said surface; a receptacle in which the lower end portion of the

hollow humidifying element is received for catching and accumulating excess water from said surface of the element, said receptacle being movable relatively to the element in response to the weight of water accumulating therein, water accumulating in said receptacle being heated by the lower end portion of the humidifying element immersed therein and evaporated thereby to increase the capacity of the device; and means responsive solely to the quantity of water accumulated in the receptacle for regulating the operativeness of said water supply means and to render said supply means ineffective upon accumulation of a predetermined amount of water in the receptacle.

13. A device of the character described comprising: a humidifying element having a moisture retaining surface adapted to be subjected to heat so as to effect diffusion of water vapor to the atmosphere; water supply means for delivering water to said element to flow down said surface thereof; a receptacle; means mounting the

receptacle adjacent to the bottom of the humidifying element in position to catch and accumulate excess water dripping from the element and for movement relative to the humidifying element in response to the accumulation of water in the receptacle; and means actuated by movement of the receptacle relative to the humidifying element for regulating the operativeness of said water supply means.
